COMBINED SUPERCHARGER AND AIR CLEANER

Roland P. Baile, Medford, Md., and Carey W. Hord, New York, N. Y., assignors to Standard Supercharger Corporation, New York, N. Y., a corporation of New York

Application October 18, 1939, Serial No. 300,052

5 Claims. (Cl. 183—21)

This invention relates to improvements in a combined supercharger and air cleaner for automotive engines.

In United States Patent No. 2,196,332, granted April 9, 1940, on copending application Serial No. 189,692, filed February 9, 1938, there is disclosed and claimed a combined supercharging and air cleaning device for mounting on the carburetor of an automotive engine and adapted for positioning in a moving air stream as, for example, that induced by the fan of the water cooling system of an automotive engine, or to be otherwise located where it can receive air at the underhood air pressure that is built up by the forward motion of the automobile itself, the device collecting the moving or pressure air and delivering it to the carburetor. The collected air is caused to move in a path such that its pressure and velocity are increased while at the same time the air stream is given a pronounced centrifugal motion whereby dirt and dust particles are separated from the air under the influence of centrifugal force, means being provided to prevent reentrainment of the separated dirt particles in the moving air stream. A device as above described thus provides an increased volume of clean air for the carburetor whereby to increase the air content of the air-gas mixture.

The present invention is directed to a combined supercharger and air cleaner which embodies the principles of the device of the aforementioned application and which is further characterized by features of improved construction and design. Thus in a device built in accordance with the present invention a minimum amount of mounting space is required, this being important from the standpoint of mounting the device in the restricted space available to it according to automobile engine and hood construction of current design. The present invention further contemplates a combined supercharging and air cleaning device as aforesaid which may be cast, pressed or otherwise fashioned in sub-assembly sections capable of ready assembly. The improved design further incorporates simplified and highly efficient means of securing the assembled device to the engine carburetor whereby a substantially fast connection is assured without rattling and vibration noises. Another important feature of the improved device resides in the means herein employed to prevent reentrainment of the separated dirt particles in the moving air stream, even under conditions of high engine speed and consequent high air velocity.

Other objects will be in part obvious and in

part hereinafter pointed out in connection with the following analysis of this invention wherein is illustrated an embodiment of the invention.

In the drawing—

5 Fig. 1 is a side elevation of a combined supercharger and air cleaner in accordance with the present invention mounted on a typical automobile engine;

10 Fig. 2 is a perspective of the device shown in Fig. 1, with one side removed whereby the interior arrangement may be viewed;

15 Fig. 3 is a vertical longitudinal section taken through the device illustrated in Figs. 1 and 2.

Referring now to the drawing wherein like reference characters designate like parts throughout the several views, the combined supercharger and air cleaner of the present invention is shown to be constituted by an upper section 10 and a lower section 11, the sections being 20 secured along the meeting line 12 by means to be described. The present invention contemplates that each of the sections 10 and 11 shall be formed integral, with the constituent curved walls of each section being of curvature or having 25 radii such as to permit removal of the forming parts or dies employed in the fashioning of the sections.

The sections 10, 11 are each provided with spaced side walls, of which the related side walls 30 10a, 11a are designated, the lower edge of the side walls 10a of the upper section engaging against the upper edge of the side walls of the lower section. The upper section 10 has a top wall, the relatively forward portion of which 35 flares upwardly as at 10b, and the relatively rear portion of which extends downwardly along an arc of relatively fixed radius, thus to form the rear wall 10c of the device.

Intermediate the forward and rear ends of the 40 device and bridging the side walls 10a of the upper section is an upwardly convex bridge piece 10d having a forwardly extending portion 10e which is shown to extend straightway and is inclined about 30° to the horizontal. The portion 45 10e terminates on a line in the plane of the meeting line 12 of the sections. The relatively rearward portion of the bridge is arched to extend along an arc of substantially constant radius and terminates in a horizontal rear edge which also 50 corresponds to the meeting line 12. It will be here understood that the arcs of constant radii along which extend the rear portion 10c and the bridge piece 10d are struck from different centers which are so related that the cross-sectional area 55 of the passage formed between the side walls 10a,

the top and rear wall 10b, 10c and the upper surface of the bridging member 10d is gradually reduced from front to rear of the passage.

Also extending between the side walls 10a of the upper section is a generally vertical web or partition 10f whose lower edge corresponds to the meeting line 12 of the sections and whose upper edge is spaced from the under surface of the bridge piece 10d to provide an opening 10g. As will be apparent from Fig. 3, the partition curves 10 somewhat rearwardly along a line which, if continued, would merge into the downwardly curved forward portion of the bridge piece 10d.

Considering now the construction of the bottom section 11, this is fashioned to provide a generally horizontal bottom wall 11b which may flare downwardly adjacent its forward portion, its rear portion extending upwardly as at 11c along a curve of substantially constant radius, and terminating in an upper edge which engages 20 against the lower edge of the rear wall 10c of the upper section 10 and along the meeting line 12. Extending between the side walls 11a of the lower section and substantially above the level of the bottom wall 11b is an upwardly concaved bridge 25 piece 11d which extends along an arc of relatively great radius, and terminates in a rear edge which meets the lower rear edge of the upper bridge piece 10d at the section meeting line 12. The bridge 11d at its forward edge terminates 30 substantially in the plane of the meeting line 12 and substantially rearwardly of the partition 10f of the upper section. By reference to Fig. 2 particularly, it will be seen that the lower bridge piece forms with the bottom wall 11b a passage 35 in continuation of the passage of the upper section.

The lower bridge piece 11d has an opening 11e therein, such constituting the inlet to a vertically arranged outlet tube 11f which is preferably 40 integral with the lower section to extend through the air passage therein and which opens through the lower wall 11b. Tube 11f is provided adjacent its forward portion with a streamlining nose or extension 11g, such serving to minimize eddying 45 of the air as it sweeps past the sides and relatively forward portion of the tube.

The lower section 11 is provided with a transverse lip or dam 11h which extends between the side walls 11a and upwardly from the bottom wall 11b, being sloped or curved along an arc such as to direct the air flow in upward direction. The portion 11h terminates well below the upper edge 50 of the side wall 11a as will be clearly seen in Fig. 3.

From the forward edge of the bottom wall 11b there extends an inclined wall 11j having an inclination corresponding to that of the portion 10e of the bridge piece 10d, its upper edge meeting the lower forward edge of the portion 10e along the meeting line 12. The inclined walls 10e and 11j cooperate with the top wall of the upper section and the side walls of the sections to provide a funnel-shaped air scoop through 55 which air enters the device.

By reference particularly to Fig. 3, it will be seen that upon assembly of the sections, a chamber 30 is provided in advance of the lip or dam 11h, such chamber being closed from the top and front by the inclined wall portions 10e and 11j, 70 on its sides by the side walls 11a and on its bottom by the bottom wall 11b of the lower section. Within such space a quantity of oil may be maintained, the depth of which is determined by the height of the dam 11h.

One simple means of securing the sections in assembled relation is illustrated in Fig. 3, such being comprised by the vertical bolt 13 the lower end of which is threaded into the streamlining nose 11g. The bridge piece 10d and the upper wall 10b of the upper section are each provided with vertically aligned bosses which are suitably drilled as indicated, to receive the upper portion of the bolt 13. A wing nut 18 threaded on to the upper threaded end of the bolt 13 and bearing on the upper boss may thereupon be utilized to secure the upper section to the lower section in detachable manner.

In order to locate properly the sections with reference to each other, one of the sections, such as the upper section, may be provided along its lower edge with downwardly extending tongues 10h and 10j which engage in suitable notches in the wall parts 11c and 11j of the lower section. This tongue and notch arrangement insures that the parts are properly aligned prior to securing the sections fast to each other and maintains proper alignment thereafter.

As will be apparent from Fig. 2, the sectional structure as described above, when assembled, provides an air passage having a large area inlet portion, as defined by the side walls 10a, 11a, the flared top wall 10b, and the inclined bottom wall portions 10e, 11j, through which air may enter in a generally horizontal path. As the passage progresses from its substantially horizontally disposed inlet portion, the cross-sectional area thereof is gradually reduced, the passage terminating in the vertical outlet tube 11f through which air entering the enlarged area inlet and moving through the passage is finally discharged. It will further be observed that the air passage through the device from the horizontally disposed inlet to the vertical outlet extends along a vertically disposed spiral or loop arranged about a horizontal axis, with the outlet tube 11f extending through the lower portion of the air passage. Accordingly, by reason of the reduction in area of the inlet passage the pressure and velocity of the air is increased. Further, due to the spiral path of travel, the air is given a pronounced centrifugal motion, with the result that dirt particles separate from the air stream and tend to collect in the lower portion of the passage under the influence of gravity.

This tendency of the dirt particles, following their separation, to collect in the low level portion or region of the air passage, while pronounced at low engine speeds, may be overcome by the air moving at high velocity at the high engine speeds and, unless means are provided to prevent their reentrainment, the separated dirt particles would be picked up by the air stream and blown through the device into the carburetor.

Means to prevent reentrainment of the separated dirt particles into the moving air stream are herein provided, such preferably including a generally horizontally air-stream splitting plate 11p which extends transversely between the side walls 11a and intermediate the bottom wall 11b and the bridge piece 11d of the bottom section. Preferably, the plate 11p is arranged at a level so as to divide the air passage throughout the lower portion of its loop or spiral formation and form a major or main air stream and a lesser air stream, the latter flowing relatively outwardly of the main air stream. As illustrated in Fig. 3, the splitting plate 11p preferably terminates in a rear edge which is disposed slightly to the rear

of the outlet tube 11f, although under certain conditions the plate may curve upwardly to terminate at or near the meeting line 12. The relatively forward portion of the plate is curved upwardly and terminates in a horizontal edge corresponding to the meeting line 12 to engage, when the sections are assembled, the lower edge of the partition 10f of the upper section.

As will be seen from the directional arrows of Fig. 3, the entering air stream in its downward course of travel is given a pronounced centrifugal motion, with effective dirt separation taking place in that portion of the air passage wherein the air moves downwardly and forwardly, with the dust particles being thrown relatively outwardly. Thereafter the air stream is split by the plate 11p, the major body of air moving above the plate and being deflected by the upper face thereof and thereafter by the under face of the arched bridge piece 10d towards the opening 11e constituting the inlet to the vertical outlet tube 11f. Thus the dirt particles separated as in the foregoing are acted upon only by the lesser body or stream of air which flows in the space between the upper surface of the wall 11b and the under face of the splitting plate 11p.

The lesser and relatively outer air stream moves forwardly along its path of travel and thence upwardly, and thereupon rejoins the main air stream upon passing over the upper edge of the partition 10f. It will be noted that the air opening 10g through which the lesser air stream rejoins the main stream is at a relatively high point in the loop-shaped path of air travel, and that the air passing through said opening must substantially reverse its direction of flow. Hence the dirt particles tending to move forwardly with the lesser air stream particularly when the air is moving at high velocity due to high engine speeds, are thrown outwardly and relatively forwardly by centrifugal action and thereupon fall into the chamber 30, in which they collect. Reentrainment of the separated dirt particles into the main air stream is accordingly prevented.

To further assist in the collection of the separated dirt particles, a dust-trapping substance such as oil may be maintained in chamber 30 at a level determined by the height of the lip or dam 11h. Preferably an excess of oil is employed so that when the automobile is on level ground, with the engine cut off or operating at a low R. P. M., the excess oil collects in the lower portion of the air passage, that is to say, rearwardly of the dam 11h. This excess oil in the air passage functions to collect dirt particles falling or otherwise moving to the lower portion of the air passages. As the engine is started and/or its speed increased, the velocity of the air moving in the passage is also increased, the air now tending to move the excess oil forwardly with it, thus to spread the excess oil over the upper surface of the dam 11h and hence to increase the area of the oil-coated surfaces on which the dust particles may collect. At high engine speeds and consequent high air velocity, the air blows the excess oil forwardly into the chamber 30, from whence it strives to return by gravity to the lower level air passage against the action of the moving air stream. The upward and thence rearward path of air travel prevents the excess oil from the air passage or oil from the chamber 30, as well as dust particles trapped thereby, from moving onward from the air stream.

Under ordinary driving conditions where up and down grades are encountered, oil continuous-

ly moves from the chamber 30 to the lower level portion of the air passage and back to the chamber. Thus when the automobile is being driven on an up grade, oil in quantity depending on the inclination flows over dam 11h from the chamber 30 to the air passage. Oil in the passage returns to the chamber when the automobile is thereafter driven on a down grade. Thus a continual wash or circulation of the oil from the chamber to the passage and back to the chamber takes place, whereby the oil in the passage is being continually replenished by oil from the chamber and whereby the relatively contaminated oil in the passage is returned to the chamber, where the dust particles separate out and are trapped, being prevented from returning to the air passage by the over-hang of the dam 11h.

The present invention further contemplates a simple means of securing the assembled body as described to the carburetor, in such manner that rattling and vibration noises are reduced to a minimum. To effect this advantageous result, I force-fit into the vertical outlet tube 11f a sheet steel tube 20, the lower portion of which is flared outwardly and is provided with axial incisions for flexibility. A securing band (not shown) may be disposed about the lower end of the tube 20 which in turn is adapted to be located about the intake tube of the carburetor and, upon suitable fastening, there results a simple yet effective form of securing the device to the carburetor.

It will be apparent from the above description, that the present invention provides a combined supercharger and air cleaner embodying the advantageous features of the above-referred to application Serial No. 189,692, while at the same time contemplates construction and design features of advantage which will be apparent to one skilled in the art. Thus, the sectional construction permits the formation of sections, preferably in integral manner, by conventional casting and/or metal working practices while at the same time permits of ready assembly. Further, the arrangement is such that dirt particles separated from the moving air stream by centrifugal action are effectively collected and prevented from reentrainment in the air stream even under conditions of high engine speed, whereby the cleaning function of the device is materially enhanced. Again, the present invention teaches simple means of securing the device as a whole to the carburetor, without the necessity of complicated securing means and without undesirable rattling and vibration noises as might normally occur over long running periods. Accordingly, a device of superior quality, workmanship and operation is provided.

As many changes could be made in carrying out the above construction without departing from the scope of the invention, it is intended that all matter contained in the above description or shown in the accompanying drawing shall be interpreted as illustrative and not in a limiting sense.

We claim:

1. A combined supercharger and air cleaner for attachment to the air intake of a carburetor, comprising a structure providing an air passage having a substantially horizontal inlet portion, a substantially vertical outlet portion, a connecting passage portion in the form of a spiral, said passage being of gradually decreasing section whereby to increase the forward velocity of the air flowing therethrough, the connecting

portion of the passage curving downwardly and forwardly from said inlet portion and thence upwardly and rearwardly to said outlet portion whereby dirt particles are thrown outwardly by centrifugal action, and means disposed relatively forwardly of and adjoining the upwardly and rearwardly curved portion of the air passage providing a chamber opening into the aforesaid passage portion, the chamber constituting a reservoir for a dust-trapping liquid adapted to flow between the reservoir and the lower portion of the air passage, a portion of the passage wall forming a dam for normally retaining the bulk of the liquid in the reservoir.

2. A combined supercharger and air cleaner for attachment to the air intake of a carburetor, comprising a structure providing an air passage having a substantially horizontal inlet portion, a substantially vertical outlet portion, a connecting passage portion in the form of a spiral, said passage being of gradually decreasing section whereby to increase the forward velocity of the air flowing therethrough, the connecting portion of the passage curving downwardly and forwardly from said inlet portion to a lower passage portion and thence upwardly and rearwardly to said outlet portion whereby dirt particles are thrown outwardly by centrifugal action, and means disposed relatively forwardly of and adjoining the upwardly and rearwardly curved portion of the air passage and constituting a reservoir for a dust-trapping liquid adapted to circulate between the reservoir and the lower portion of the air passage, a portion of the passage wall between the upwardly curved passage portion and the reservoir being cut away to provide communication between said passage portion and the reservoir and the remaining portion of the passage wall forming a dam for normally retaining the bulk of the liquid in the reservoir.

3. A combined supercharger and air cleaner for attachment to the air intake of a carburetor comprising upper and lower complementary sections, means for securing the sections together in assembled relation, the assembled sections providing an air passage having a substantially horizontal inlet portion, a substantially vertical outlet portion, a connecting passage portion in the form of a spiral, said passage being of gradually decreasing section whereby to increase the forward velocity of the air flowing therethrough, the connecting portion of the passage curving downwardly from said inlet portion to a lower passage portion and thence upwardly and rearwardly to said outlet portion whereby dirt particles are thrown outwardly by centrifugal action, and the assembled sections further providing means adjacent the upwardly and rearwardly curved portion of the air passage and including an opening in the outer wall of the aforesaid passage portion which is disposed above the lower passage portion for collecting dirt particles thrown outwardly from the air stream and for

preventing their subsequent reentrainment in the air stream.

4. A combined supercharger and air cleaner for attachment to the air intake of a carburetor comprising upper and lower complementary sections, means for securing the sections together in assembled relation, the assembled sections providing an air passage including a substantially horizontal inlet portion, a substantially vertical outlet portion, a connecting passage portion in the form of a spiral, said passage being of gradually decreasing section whereby to increase the forward velocity of the air flowing therethrough, the connecting portion of the passage curving downwardly from said inlet portion to a lower passage portion and thence upwardly and rearwardly to said outlet portion whereby dirt particles are thrown outwardly by centrifugal action, and the assembled sections further providing a chamber disposed forwardly of and adjoining the upwardly and rearwardly curved portion of the air passage, the relatively outer wall of the adjacent passage portion being cut away to provide opening between the passage portion and the chamber which is disposed above the lower passage portion, whereby a portion of the air stream moves in a generally upward direction through the chamber and whereby dirt particles moving along the outer wall of the air passage or otherwise carried by the air stream are thrown outwardly therefrom and collected in said chamber.

5. A combined supercharger and air cleaner for attachment to the air intake of a carburetor comprising upper and lower complementary sections, means for securing the sections together in assembled relation, the assembled sections providing an air passage including a substantially horizontal inlet portion, a substantially vertical outlet portion, a connecting passage portion in the form of a spiral, said passage being of gradually decreasing section whereby to increase the forward velocity of the air flowing therethrough, the connecting portion of the passage curving downwardly and forwardly from said inlet portion to a lower passage portion and thence upwardly and rearwardly to said outlet portion whereby dirt particles are thrown outwardly by centrifugal action, means dividing the air flowing through the connecting portion of said passage into an outer stream and an inner stream, and a chamber disposed forwardly of and communicating with the upwardly and rearwardly curved portion of the passage portion through an opening in the outer wall of the upwardly curved passage portion and which is disposed relatively above the lower passage portion, whereby the outer air stream flows through said chamber and whereby dust particles moving along the outer passage wall or otherwise carried by the outer air stream are thrown outwardly therefrom and collected in said chamber.
